TUBEFLO SECTION

William Bisch, Holmdel, N. J., assignor to The Griscom-Russell Company, New York, N. Y., a corporation of Delaware

Application June 12, 1946, Serial No. 676,178

2 Claims. (Cl. 257—241)

1

This invention relates to heat exchange apparatus and, more particularly, to an improved construction of heat exchanger.

In many industrial operations it is essential that heat be economically transferred from a comparatively hot fluid to a fluid of lower temperature. For example, the efficient operation of a petroleum refinery often depends upon the availability of such apparatus. Not infrequently in such a plant the temperatures of both the hot fluid and the cooler fluid are comparatively high, although a large temperature difference exists between them. Also, one or both of these fluids may be subjected to very high pressure. For such work, therefore, it is necessary to have heat exchange apparatus which will withstand the pressures encountered and at the same time be capable of operation without disability by reason of different degrees of expansion accompanying widely differing temperatures in closely adjacent parts.

In United States Patent No. 2,013,187, issued September 3, 1935, to Joseph Price, and assigned to the same assignee as the present application, there is described and claimed a heat exchanger of the type under consideration which is formed of comparatively thin metal tubes, pairs of such tubes having threaded upon them a large number of metal plates which are spaced slightly apart from one another and uniformly distributed along the tubes. The tubes are expanded into intimate and rigid heat exchanging contact with these plates.

Although heat exchangers constructed as just described have had a high degree of commercial success, large numbers of them having been manufactured and being now in use, nevertheless such construction possesses certain disadvantages. For example, the metal plates or fins connecting the tubes must have sufficient strength to withstand the expansion process and consequently they are usually made of ferrous metal, and this metal interposes a rather high resistance to the heat transfer. Moreover, in order for the fins to have sufficient strength it is necessary to space the tubes apart not less than about one-fourth inch and excess metal is required at the ends and sides of the fins. Consequently, the weight of the fins is a considerable factor and tends to make the overall weight of the heat exchanger heavier than desired. Furthermore, this construction is limited as to the permissible temperature difference between the tubes because of the expansion strains set up in the plates which are locked securely to the tubes by the expand-

2

ing process. Finally, the center-to-center distance between the tubes is fixed by the expanding machine and prohibits the use of a larger and a smaller tube, or tubes, in the same unit without increasing the resistance to heat flow between the tubes.

The object of the present invention is to overcome these difficulties and provide a tube-to-tube heat exchanger adapted for use at high pressures and temperatures and having greatly reduced resistance to heat transfer and which is compact and easy to clean.

Another object of the invention is to provide a heat exchanger in which the stresses of expansion and contraction are substantially eliminated, even when operating with fluids widely different in temperature.

Another object of the invention is to provide a heat exchanger in which tubes of different size may be employed without reducing the efficiency of heat transfer, and thereby enabling the proper velocity ratio between the two fluids to be maintained.

A further object of the invention is to provide a heat exchanger in which the heat conduction is substantially the same as though the passages for the hot and cold fluids were bored in a solid metal block.

A still further object of the invention is the provision of an improved method of constructing heat exchange devices of the type described.

The invention will be understood by considering the accompanying drawings and the appended claims, a preferred form of the invention and two modifications thereof being illustrated in these drawings in order to exemplify the carrying out of the invention. In these drawings:

Fig. 1 is a view in central longitudinal section of the preferred form of heat exchange unit or element constructed in accordance with the present invention;

Fig. 2 is a fragmentary perspective or projective view of the device of Fig. 1, partly in side elevation, with certain parts omitted and others shown in longitudinal section, the view being shown partly in transverse section;

Fig. 3 is a view in transverse section taken on the line 3—3 of Fig. 1;

Fig. 4 is a fragmentary transverse sectional view taken on the line 4—4 of Fig. 1 but drawn to a larger scale; and

Fig. 5 is a view similar to Fig. 1 showing a modified form of construction.

Fig. 6 is a view also similar to Fig. 1 showing another modification; and

Figs. 7 and 8 are cross-sectional views taken on lines 1-1 and 8-8 respectively, of Fig. 6.

Referring to these drawings, there is illustrated a heat exchanger having two U-shaped or hairpin-shaped tubes indicated generally by reference numerals 1 and 2 (Figs. 1 and 3). Each of the U-shaped tubes 1 and 2 may be formed in any suitable manner, for example, by bending upon itself a piece of metallic tubing of approximately twice the desired length of unit, bringing the two open ends together and forming two parallel legs 1a and 1b and 2a and 2b, respectively, connected at their opposite ends by integral return bend portions 1c and 2c. These tubes are preferably comparatively thin walled and may conveniently comprise seamless drawn tubes of steel or other suitable metal.

The open ends of tubes 1 and 2 are permanently secured in any suitable manner, for example by welding 3, to a connection flange 4. Both of these U-shaped tubes extend toward the right from connection flange 4 in substantially parallel relation. Hence, a single central pocket and four outer pockets or spaces exist and extend from end to end of the elongated tubes. Elongated core strips or filler strips 5 of generally triangular shape in cross section are placed loosely within each of the four outer pockets, and a single four-cornered core strip 6 is located within the central or inner pocket. These may be put in place either by springing apart the outer or right-hand ends of the two tubes 1 and 2, or they may be inserted before the tubes are welded to flange 4.

A metallic casing 7, preferably cylindrical in form and sealed at its right-hand end as indicated in Fig. 1, surrounds the two U-shaped tubes 1 and 2 and holds the outer filler strips 5 in place. In the drawings the clearance spaces between the outer surfaces of the tubes and filler strips and the interior of casing 7 have been purposely exaggerated for the sake of clearness. It is the intention, however, to have the casing fit over these parts with the smallest practicable amount of clearance which will permit the assembly of the casing and tubes. The inner or lefthand end of casing 7 is provided with a flange 8 and both flanges 4 and 8 may be bolted to a header 9 by means of a single ring of mounting bolts as indicated by numeral 10. It will be understood that header 9 contains fluid passages which connect with the open ends of the respective U-shaped tubes 1 and 2 for the purpose of conducting one of the heat exchange fluids through one of these tubes, tube 1 for example, and the other fluid through tube 2.

The core strips 5 and 6, in order to facilitate the transfer of heat between the legs 1a and 1b of tube 1 and the legs 2a and 2b of tube 2, may be made of copper aluminum, or a suitable alloy, although they may also be made of steel. In order to bring about intimate heat conducting contact between the surface of the several tube legs 1a, 1b, 2a, 2b, and the surfaces of the cores 5 and 6 in contact with them, the interior of casing 7 not occupied by the tubes and core strips, is filled with an interstitial material 11 which is liquid at the operating temperature of the heat exchange apparatus, although it may be solid at ordinary room temperature; that is to say, it may solidify after the apparatus has been in operation and is shut down and allowed to cool. Material 11, however, preferably has a vaporization point which is substantially above the operating temperature of the apparatus so that there will be no

vapor formation within casing 7. A number of metals are suitable for this purpose, mercury, tin, lead, and zinc, and alloys of two or more of these metals being examples. Also certain non-metallic materials may be used. One such material is available under the trade name of "Dowtherm" and consists of a mixture composed of about 26.5% diphenyl and 73.5% diphenyl oxide.

In view of the fact that the liquid interstitial material 11 provides a path of good heat conductivity between the metal of each of the tubes and the metal of the core strips 5 and 6, it is not important to have the core strips preformed to fit closely the curvature of the various tubes. As shown in Fig. 4, the core strips may contact the surfaces of the tubes at certain points but not at others, and if the unit is operated in horizontal position as shown, the core strips will rest upon the upper portions of the tubes and fall away from them along the lower sides of the tubes, the intervening spaces being automatically filled with the molten material 11 at the operating temperature of the apparatus. It is desirable, however, to preform core strips 5 and 6 so as to fill as much of the interior space of casing 7 as possible in order to reduce the amount of the more expensive material 11 required.

In order to reduce heat loss from the heat exchange unit to the surrounding atmosphere, it may be lagged or provided with a suitable covering 12 of insulating material shown in Fig. 1.

In the modification shown in Fig. 5 the heat exchange unit is constructed exactly as described in connection with Figs. 1 to 4 inclusive, except for the fact that the core strips 5 and 6 are omitted and the interstitial material 11, which is in the liquid state at the temperature of operation of the apparatus, fills all of the space within casing 7 not occupied by the U-shaped tubes 1 and 2.

In the modification shown in Figs. 6-8, the hairpin or U-shaped tubes 13 and 14 cross one another at the ends thereof remote from the connection flange 4. That is the elbow or return bend portion 14C passes through the elbow portion 13C. Flattening the inner elbow 14C, or both elbows 13C and 14C as shown, eliminates a bulge or enlargement beyond the lateral dimensions of the tube bundle leg portions 13a and 14a which would otherwise occur. In this form of the improved heat exchanger element the legs may be nested into contact with each other as shown in Fig. 7 resulting in a generally oval structure when the core strips 5m are assembled with the tubes. Inner cores 15 may be included if desired. Casing 7m is preferably oval in cross-section. In other than these respects the construction of this modification is like that described in connection with Figs. 1-4 inclusive.

It will be understood that the casings 7 and 7m may, if desired, be made in some other shape than shown, that is to say, square rectangular, hexagonal, etc., instead of round or oval; also that various numbers of U-shaped tubes 1, 2 and 13, 14 may be included in a single casing. It will be also understood that the tube or tubes to carry one of the heat exchange fluids may be of smaller diameter than the tube or tubes for the other heat exchange fluid, thus enabling the fluids to pass through the apparatus at the proper velocity ratios.

In carrying out the improved method of producing the novel heat exchanger of the invention, straight tubes of preferably seamless drawn material such as steel, and each one exactly like

the other except that certain of them may be smaller in diameter than the rest, are placed alongside of one another and assembled into a bundle with elongated core strips inserted in the spaces or pockets between them, for example as shown in Figs. 2 and 3. This assembled bundle of tubes and core strips is then surrounded by a casing of any suitable shape to fit the shape of the tube bundle. The bundle of tubes and core strips and the casing are then heated to a temperature above the melting point of the interstitial material to be used and such material in molten state is then poured into the casing and caused to fill all of the spaces within the same not occupied by the tubes and core strips. The whole is then allowed to cool, after which a suitable connection flange or flanges may be applied to the ends of the tubes.

By means of the present invention a heat exchanger unit has been provided which is well adapted for use both at high pressures and high temperatures and which accomplishes the transfer of the heat from the comparatively hotter fluid to the cooler fluid with a minimum of loss, the heat conduction being substantially the same as though the two fluids were passing through closely adjacent bores in a solid block of metal.

It will be understood that the apparatus illustrated herein to exemplify the manner in which the invention can be carried out is capable of considerable variation and that changes may be made without departing from the spirit of the invention as set forth in the appended claims.

I claim:

1. A composite heat exchanger unit including two substantially parallel juxtaposed pre-fabricated metallic tubes, a plurality of pre-fabricated metal fillers positioned to fill substantially all of the space between the outer walls of said tubes along substantially the entire length thereof and a casing enclosing said fillers and tubes with a small clearance between the inner surface of said casing and the surface of said fillers and tubes so as to maintain said fillers and

tubes in close association, said casing containing interstitial liquid filling all of the space therewithin not occupied by the fillers and tubes and the outer surface of said tubes being thermally united by said liquid with the contiguous surface of said fillers.

2. A composite heat exchanger unit including two substantially parallel juxtaposed pre-fabricated metallic U-shaped tubes, a plurality of pre-fabricated metal fillers positioned to fill substantially all of the space between the outer walls of said tubes along substantially the entire length thereof and a casing enclosing said fillers and tubes with a small clearance between the inner surface of said casing and the surface of said fillers and tubes so as to maintain said fillers and tubes in close association, said casing containing interstitial liquid filling all of the space therewithin not occupied by the fillers and tubes and the outer surface of said tubes being thermally united by said liquid with the contiguous surface of said fillers.
